DOOR LOCK

Russell W. Ahlquist and Leland H. Fisler,
New Britain, Conn.

Application January 23, 1956, Serial No. 563,138

(Filed under Rule 47(a) and 35 U. S. C. 116)

11 Claims. (Cl. 292—169)

This invention relates to a door lock, and more particularly to a door lock of the type commonly referred to as a "cylindrical door lock," which includes novel dogging means for selectively dogging the outer operating member of the door lock to prevent retraction of the latch bolt and opening of the door.

The structure of the dogging means disclosed herein constitutes an improvement over the dogging means disclosed in United States Patent No. 2,724,607, dated November 22, 1955, and is intended for use in the same cylindrical door latch operating unit originally disclosed in United States Patent No. 2,733,088, dated January 31, 1956; said operating unit being intended for use on passage doors, but adapted to receive, through the rotatable knob spindles thereof, other components that co-act with the elements of the basic unit to render to said unit various locking functions.

The cylindrical door lock illustrated in Patent No. 2,724,607, and particularly in Fig. 9 thereof, was intended for use on bathroom and bedroom doors and included a dogging bar having a head portion which was cammed rearwardly relatively to the lock case into dogging position upon depression of the pushbutton extending from the inner knob. As the head portion of the dogging bar moved towards dogging position, it urged the retractor of the lock rearwardly against the retractor springs until the dogging bar reached dogging position whereupon said retractor was returned to its normal position by the said springs and engaged an abutment on the bar which retained the bar in dogging position until released by retraction of the retractor through rotation of the inner knob or depression of the latch bolt. The head of the dogging bar of the prior structure was provided with a finger which, when the bar was in dogging position, was disposed in aligned slots in the outer knob spindle and in the stationary knob spindle bearing and prevented rotation of said outer knob spindle. It was found, through extensive use of the prior door lock, that depression of the pushbutton required an excessive amount of force since the dogging bar was required to urge the retractor rearwardly against the relatively heavy retractor springs. Furthermore, if the dogging bar had been inadvertently moved into dogging position when the door was open, and the outer knob was turned while the door was being closed, the dogging finger on the dogging bar would be pinched between the stationary bearing and the outer spindle and the dogging bar would not be released as the door was closed, thereby preventing operation of the outer knob and re-entry into the room.

The primary object of the present invention, therefore, is the provision of improved dogging means for a cylindrical door latch operating unit which are insertable into the unit through the inner spindle thereof and which require the use of very little force to be moved into dogging position.

A further object of this invention is to provide such novel dogging means which include a blocking element that positively prevents re-engagement of the retractor

2

therewith once the retractor has been urged into retracted position, such as when the door is closed and the latch bolt is depressed.

The primary objects of this invention are attained by 5 providing a dogging bar which is cammed into dogging position as in the prior structure, but which carries a latching bar that is under light spring pressure and is depressed against the retractor relatively to the dogging bar against said light spring pressure during movement 10 of the bar towards dogging position, thereby eliminating the necessity of moving the retractor against the relatively heavy retractor springs, and which is provided with abutment means that are moved into engagement with the retractor to hold the dogging bar in dogging position.

15 In addition, said latching bar is provided with a blocking element which prevents re-engagement of the retractor with the abutment thereon once said retractor has been moved out of engagement therewith.

Further objects and advantages of this invention will be 20 more clearly understood from the following description and the accompanying drawings in which:

Fig. 1 is a plan view, partially in central horizontal section, of the operating unit of the cylindrical door lock embodying the instant invention and illustrating the dogging means therein when in undogging position.

25 Fig. 2 is an end view of said operating unit taken substantially on line 2—2 of Fig. 1.

Fig. 3 is a similar view taken on line 3—3 of Fig. 1.

30 Fig. 4 is a fragmentary plan view of the dogging bar and latching bar employed in the operating unit of the door lock.

Fig. 5 is a sectional end view of the operating unit taken on line 5—5 of Fig. 1.

35 Fig. 6 is a similar view taken on line 6—6 of said Fig. 1.

Fig. 7 is a sectional end view of the pushbutton on said dogging bar on lines 7—7 of Fig. 1.

40 Fig. 8 is a fragmentary view similar to Fig. 1 illustrating the dogging bar and the latching bar as they are being moved toward dogging position.

Fig. 9 is a fragmentary view again similar to Figs. 1 and 8, but illustrating the dogging means in dogging position.

45 Fig. 10 is a fragmentary plan view, partially in section, illustrating the operation of the blocking means which prevent re-engagement of the retractor with the latching bar on the dogging bar.

Referring to the drawings wherein the operating unit of the cylindrical door lock is shown, it will be noted that 50 said operating unit includes a casing, generally indicated at 5, which houses and supports the latch operating mechanism and includes an inner end plate 6 and an outer end plate 7 having integral tubular sleeves 8 and 9 extending, respectively, therefrom; the end portion of each 55 of said sleeves being of a reduced diameter. A U-shaped retractor guide is secured between the end plates 6 and 7 and has spaced parallel arms 10—10 which extend transversely across the casing 5 equidistant from the longitudinal axis of the operating unit.

60 A retractor 11 is slidably supported between the arms of said retractor guide and is preferably constructed from a single piece of sheet metal. Said retractor includes an inner side 12 from which are bent spaced parallel legs 13—13. The rear portion of each of said legs has an extension 14 thereon and said extensions are bent over, parallel to the inner side 12, to form the outer side of the retractor. The inner side 12 of the retractor is also provided with extensions which are bent perpendicularly thereto and extend across the retractor intermediate its 65 ends to provide rollback platforms 15—15 thereon. The edges of the extensions 14—14, which form the outer side of the retractor, and the edges of the rollback plat-

forms 15—15 are spaced apart a distance equal to the width of a slot 16 extending into the inner side 12 of the retractor to provide a transverse opening therethrough. The outer ends of the retractor legs 13—13 are bent to provide the conventional oppositely disposed fingers 17—17.

The retractor guide carries a spring seat 18 which supports a pair of compression springs 19—19 whose free ends are disposed between the inner and the outer sides of the retractor and engage ears that project from the opposite sides of a U-shaped guard member 20 that extends across the retractor; the side portions of said guard being spaced apart a distance substantially equal to the width of the slot 16. It will be understood that the compression springs 19—19 retain the ears on the guard member 20 against the backs of the rollback platforms 15—15 and urge the retractor into its normal extended position as best illustrated in Fig. 2.

The inner sleeve 8 and the outer sleeve 9 contain similar bearing members 21 and 22, respectively, which are prevented from rotating therein by means of tabs 23 and 24 which are bent inwardly from said sleeves and project into slots 25 and 26 extending the entire length of said bearings. The formation of the tabs 23 and 24 results in the provision of slots 27 and 28 in the inner and the outer sleeves, respectively, which are disposed in alignment with the slots 25 and 26 in the bearings 21 and 22. Movement of each of said bearings longitudinally of its respective sleeve is prevented by means of fingers 29 and 30 which are bent inwardly into notches formed in the edges of the bearings.

Inner and outer tubular spindles 31 and 32 are rotatably supported by the bearings in the inner and the outer sleeves, and said spindles have segmental portions 33 and 34 projecting therefrom into the casing 5. The opposite edges of said segmental portions are bent outwardly to provide rollbacks thereon which engage the rollback platforms 15—15 of the retractor to both limit the outward movement thereof by the springs 19—19 and to cause rearward movement thereof when either of the spindles is rotated. The free end of each of said segmental portions 33 and 34 is upwardly inclined to provide abutments 35 and 36 between said rollbacks for a purpose to be hereinafter more fully described. The spindles 31 and 32 contain longitudinally extending slots 37 and 38 which are normally disposed in alignment with the slots in the bearing members and in the sleeves, as illustrated in Figs. 1 and 3, and said spindles are rotatably retained within the operating unit by annular thrust washers 39 and 40 as fully disclosed in United States Patent No. 2,751,244, dated June 19, 1956.

The inner spindle 31 carries an inner knob 41 and the outer spindle 32 carries an outer knob 42; said knobs having tubular shanks which telescopically receive said spindles and enter the reduced end portions of said sleeves to provide a bearing for the outer ends of the spindles. Each of the knobs is retained on its spindle by a knob retainer 43 of the type fully disclosed in United States Patent No. 2,739,006, dated March 20, 1956. The knob retainer in each of said spindles is retained therein by means of an ear 44 which is bent inwardly into the spindle, and said retainer is urged to retaining position by a suitable spring member 45 that is secured within the spindle.

The entire mechanism above described is maintained in assembled position by a cup-shaped cover 46 which is secured in position over the end plates 6 and 7 and also provides for attachment of a conventional latch unit 47, shown in dotted lines in Fig. 3, that includes a latch bolt 48 having a retractor bar 49 extending therefrom. Said retractor bar is provided with slots adjacent its inner end which receive the fingers 17—17 on the retractor when the latch unit is connected to the operating unit in the conventional manner.

It will be understood from the above description that

rotation of the inner knob 41 or the outer knob 42 will rotate its respective spindle and, through the engagement of the rollbacks thereon with the rollback platforms on the retractor, urge the retractor rearwardly to withdraw the latch bolt from the conventional strike (not shown) to permit opening of the door. It will also be understood that whenever the door is closed and the latch bolt is depressed upon engagement with the strike, the retractor will be urged rearwardly therewith due to the manner in which the retractor fingers are connected to the retractor bar of the latch unit.

The present invention is embodied particularly in novel dogging means for the operating unit above described which are selectively operable to prevent rotation of the outer spindle 32, and consequently the outer knob 42, to thereby render the lock inoperable from the outer side of the door.

The said dogging means is in the form of a dogging unit which, in the embodiment of the invention illustrated, is insertable into the inner spindle 31 of the operating unit and includes a flat dogging bar 50 which extends longitudinally through the spindle and has a head portion 51 normally disposed in the position illustrated in Fig. 1. Said head portion 51 has a dogging finger 52 extending rearwardly therefrom which, when in normal position, extends into the opening in the retractor and lies between the sides of the guard member 20 carried thereby. The front edge of said head portion contains a laterally extending projection 53 having an angularly disposed cam surface 54 which extends from the edge of the projection to the front edge of the said head portion which normally rests upon the edge of the abutment 35 that extends between the rollbacks of the inner spindle. The dogging bar extends through the inner spindle and contains a notch 55 in its front edge adjacent its outer end portion.

The dogging unit also includes a flat latching bar 56 which is disposed rearwardly of said dogging bar 50 and co-planar therewith and has a semi-circular projection 57 extending laterally from its front edge adjacent its outer end which is received in a semi-circular recess 58 in the rear edge of the dogging bar 50 and pivotally mounts the latching bar thereon. The said latching bar has a head portion 59 at its inner end which extends under the edge of an outwardly extending projection 60 on the dogging finger 52 which provides a stop that limits pivotal movement of the latching bar rearwardly relatively to the dogging bar. The head portion 59 of the latching bar contains a notch 61 in its rear edge, and from said rear edge there also extend spaced projections 62 and 63; the projection 62 being disposed directly adjacent the notch 61 and having a hole 64 extending longitudinally therethrough, and the projection 63 having a hole 65 extending transversely therethrough. The outer end portion of the latching bar contains a notch 66 in its rear edge which is disposed oppositely to the notch 55 in the dogging bar and the edges of said notches provide seats for the opposite end portions of a flat C-shaped spring 67 which normally biases the latching bar about its pivot and urges the edge of the head portion thereon toward the edge of the slot 16 in the retractor and against the edge of the projection 60 on the dogging finger 52. The spring 67 also acts to retain the projection 57 on the latching bar in the recess 58 in the dogging bar.

The dogging bar and the latching bar are moved by means of a pushbutton 68 which is contained in the inner spindle and extends through an axial opening in the inner knob. The pushbutton consists of a hollow cylindrical member 69 having an enlarged open inner end 70 which receives a cup-shaped spring support 71 that is retained in the open end of the pushbutton by opposed lugs 72 which are bent from said pushbutton over the edge of said spring support. The spring support has a circular opening 73 in its wall through which the outer ends of

the dogging bar and the latching bar extend, and the spring member 67 which is attached to said bars is contained within the pushbutton 58. The outer ends of the dogging bar and the latching bar are maintained in alignment by a disk 74 which is contained within the pushbutton against the wall of the spring support and has a rectangular slot 75 therein through which the said bars extend. The wall of the spring support and the adjacent disk 74, which form the inner end wall of the pushbutton, are contained between the inner edges of the notches 55 and 66 and the ends of the flat spring 67, which is wider than said bars and the slot 75, to thereby secure the pushbutton to said bars. However, said pushbutton is free to rotate relatively to the bars with the inner knob.

Said dogging unit also includes a cup-shaped spring support 76 which is contained within the inner spindle and is disposed against the ear 44 which is bent inwardly therefrom to prevent detachment of the knob retainer 43. Said support 76 has a circular opening through its wall portion through which the dogging bar and the latching bar extend and is provided with a notch in its periphery to accommodate the structure in the spindle that secures the knob retainer spring 45 therein. The inner ends of the dogging bar and the latching bar are maintained in proper alignment by a disk 77, similar to the disk 74, having a rectangular slot 78 therethrough through which said bars extend. The disk 77 is disposed adjacent the spring support 76 and is cut away to prevent interference thereof with the ear 44 against which the spring support rests.

A compression spring 80 is disposed between the spring support 76 in the inner spindle and the spring support 71 in the pushbutton and urges the pushbutton and the dogging bar and latching bar into their normal undogging positions as illustrated in Fig. 1.

The latching bar carries blocking means for preventing reengagement of the retractor therewith when the dogging bar is in dogging position and said blocking means comprises a U-shaped spring member 81 which lies alongside of the latching bar and the dogging bar and has one end thereof extending through the hole 65 in the projection 63 to secure the spring thereto. The opposite free end 81-a of said spring extends through and is slidable in the hole 64 in the projection 62 and is normally disposed over the notch 61 in the latching bar and rearwardly of the edge of the head portion thereof as illustrated in Figs. 1, 4 and 8.

When it is desired to dog the outer knob against rotation from the inner side of the door, the pushbutton is depressed against the force of the spring 80, thereby causing longitudinal movement of the dogging bar and the latching bar with respect to the inner spindle and through the opening in the retractor. As the said bars move toward the outer spindle, the cam surface 54 on the dogging bar engages the abutment 35 on the segmental portion 33 of the inner spindle and biases the head portion 51 of the dogging bar rearwardly, with respect to the casing 5, to cause entry of the dogging finger 52 into the aligned slots 38, 26 and 28 in the outer spindle, bearing and sleeve, respectively. The head of the latching bar is, however, prevented from moving rearwardly with the dogging bar due to the engagement of its edge with the edge of the slot 16 in the retractor. The dogging bar therefore pivots toward the latching bar about the projection 57, as shown in Fig. 8, and the outer end of the dogging bar moves away from the outer end of the latching bar against the force of the spring 67. Since the bars are pivoted near their outer ends, it requires very little force to move the inner ends of the bars together and depression of the pushbutton requires very little effort.

When the bars reach dogging position, as illustrated in Fig. 9, the notch 61 comes into alignment with the edge of the slot 16 in the retractor and the spring 67 then urges the latching bar about its pivot and into its normal

position to bring the sides of said notch 61 over the edge of the slot 16 in the retractor to thereby prevent movement of the dogging bar into undogging position by the spring 80. During movement of the dogging bar and latching bar into dogging position, it will be noted that the retractor is at all times retained in normal projected position by the retractor springs 19-19 which are of sufficient strength to resist the force exerted by the spring 67 on the latching bar 56.

Referring now to Fig. 9 wherein the dogging bar is illustrated in dogging position, it will be understood that rotation of the inner knob or depression of the latch bolt upon closing of the door will urge the retractor rearwardly to thereby disengage the edge of the slot 16 from the notch 61 in the latching bar to permit movement of the bars and the pushbutton to normal undogging position under the force of the spring 80. As the dogging bar and the latching bar move outwardly towards undogging position after being released by the retractor, they are urged forwardly by the retractor, as it returns toward normal position, through the engagement of the edge of the slot 16 with the rear edge of the head on the latching bar. It will be noted that upon retraction of the retractor, as above described, the latching bar is prevented from following the retractor due to the engagement of the head portion thereof with the projection 63 extending inwardly from the dogging finger.

As the latching bar and dogging bar approach dogging position, as illustrated in Fig. 9, the end 31-a of the spring 81 will engage the inner side of the retractor and will be depressed while the latching bar moves inwardly relatively thereto into latching position. The spring 81 will then assume the position illustrated in Fig. 9 wherein its free end portion 81-a is held in retracted position by engagement with the side portion of the retractor. If movement of the dogging bar into dogging position should occur accidentally while the door is open, and upon closing the door a person grasps the outer knob and turns it, it will be understood that the dogging finger 52 will be pinched between one side of the slot in the spindle and the opposite side of the slot in the bearing 22 so that, when the retractor is urged rearwardly upon depression of the latch bolt, the spring 80 will be prevented from returning the dogging unit to undogging position. If it were not for the provision of the blocking spring 81, the retractor would come forwardly when the latch bolt entered the opening in the strike and the side portion of said retractor would reenter the notch 61 and hold the dogging unit in dogging position after the knob was released, thereby preventing operation of the outer knob. The blocking spring 81 prevents such an occurrence because as soon as the side of the retractor is urged out of the notch 61 upon depression of the latch bolt and to the position illustrated in Fig. 10, the end 81-a of the blocking spring is projected over the entrance to said notch and prevents re-entry of the side of the retractor therewith. When the retractor returns to normal position upon entry of the latch bolt into the opening in the strike, the edge of the slot 16 will engage the end of the spring and pivot the latching bar toward the dogging bar against the spring 67. When the outer knob is released and the dogging finger is thereby freed, the spring 80 will then immediately return the dogging bar and the latching bar to their normal undogging positions.

We claim:

1. A door lock including a retractor, a latch bolt connected to said retractor, means for retracting said retractor to withdraw said latch bolt, dogging means for preventing operation of said retracting means, latching means carried by said dogging means engageable with said retractor for retaining the dogging means in dogging position, and blocking means on said latching means normally in a position preventing engagement of said latching means with said retractor; said blocking means being movable to an inoperable position upon movement of the

dogging means into dogging position to permit engagement of said latching means with the retractor and being movable into blocking position upon retraction of said retractor and disengagement thereof from said latching means.

2. A door lock including a retractor, a latch bolt connected to said retractor, means for retracting said retractor to withdraw the latch bolt, dogging means for preventing operation of said retracting means, latching means carried by said dogging means engageable with said retractor for retaining the dogging means in dogging position, a blocking spring associated with said dogging means and having a portion normally disposed in a position preventing engagement of said latching means with said retractor; said portion being engageable with said retractor upon movement of the dogging means into dogging position and movable to a retracted position to permit engagement of said latching means with the retractor; said blocking spring being operable to project said portion into blocking position upon depression of said retractor to prevent re-engagement of said retractor with said latching means.

3. A door lock including a retractor, a latch bolt connected to said retractor, operating means for retracting said retractor to withdraw the latch bolt, a dogging unit including a dogging bar having a dogging finger thereon adapted to dog said operating means against operation and a latching bar carried on said dogging bar and having a notch therein adapted to receive an edge portion of said retractor to latch the dogging bar in dogging position, spring means normally urging said latching bar into latching position, a blocking spring carried on said latching bar and having an end portion normally disposed over said notch to prevent latching engagement of said latching bar with said retractor, said blocking spring being compressible upon engagement of said end portion with said retractor when the said unit is moved into dogging position to permit movement of said latching bar into latching engagement with said retractor; said end portion of said blocking spring being projected into blocking position upon movement of said retractor from said notch to prevent re-engagement of the retractor therewith while the dogging unit remains in dogging position, and means for moving said bars to undogging position.

4. In a door lock, a retractor for a latch bolt movable between projected and retracted positions and having an opening extending transversely therethrough providing an edge portion on the inner side of said retractor, a dogging unit movable through said opening transversely of said retractor between undogging and dogging positions, said dogging unit including a dogging bar and a latching bar pivotally connected intermediate their ends and having their inner ends extending into said opening, a latching abutment on the inner end of said latching bar adapted to engage said edge portion, a hollow pushbutton attached to the outer ends of said bars, a spring contained within said pushbutton and acting upon the outer ends of said bars to urge the inner end of the latching bar toward the edge portion of the opening in said retractor, said pushbutton, when depressed, shifting said dogging unit into dogging position wherein said spring will move said latching bar to cause engagement of said latching abutment with said edge portion to retain the dogging bar in dogging position, and separate spring means for shifting said dogging unit to undogging position upon retraction of said retractor and disengagement of said edge portion from said latching abutment.

5. In a door lock, a retractor for a latch bolt movable between projected and retracted positions and having an opening extending transversely therethrough providing an edge portion on the inner side of said retractor, a dogging unit movable through said opening transversely of said retractor between undogging and dogging positions, said dogging unit including a dogging bar and a latching bar lying in a common plane with the latching bar adjacent

said edge portion, a latching abutment on said latching bar adapted to engage said edge portion, a projection on the edge of one of said bars intermediate its ends extending into a recess in the adjacent edge of the other of said bars whereby said bars are arranged for relative pivotal movement, a hollow pushbutton secured to the outer ends of said bars and adapted upon depression thereof to shift said bars through said opening and into dogging position, a spring contained within said pushbutton and acting upon the outer ends of said bars to bias the inner end of the latching bar toward the edge portion of the opening in said retractor to cause engagement of said latching abutment therewith to retain the dogging bar in dogging position, and separate spring means for shifting said dogging unit into undogging position upon retraction of said retractor and disengagement of said edge portion from said latching abutment.

6. In a door lock, a retractor for a latch bolt movable between projected and retracted positions and having an opening extending transversely therethrough providing an edge portion on the inner side of said retractor, a dogging unit movable through said opening transversely of said retractor between undogging and dogging positions, said dogging unit including a dogging bar and a latching bar lying in a common plane in edge-to-edge relationship with the latching bar adjacent said edge portion, said latching bar being pivotally mounted intermediate its ends to said dogging bar and having a latching abutment thereon engageable with said edge portion, means providing outwardly facing abutments on the opposite edges of said bars adjacent their outer ends, a hollow pushbutton having an inner end wall containing an opening through which the outer ends of the bars extend, a C-shaped spring member of greater width than said bars contained within said pushbutton with its opposite ends seated upon the opposite edges of said bars and biasing the latching bar about its pivot to urge the inner end thereof toward said edge portion, the end wall of said pushbutton being disposed between said abutments and the ends of said spring whereby said pushbutton is secured to the outer ends of said bars and, upon depression thereof, will cause movement of said bars through the opening in said retractor and into dogging position wherein said latching abutment will engage said edge portion under the influence of said spring to retain the dogging unit in dogging position, and separate spring means for shifting the dogging unit to undogging position upon retraction of said retractor and disengagement of said edge portion from said latching abutment.

7. In a door lock, a retractor for a latch bolt movable between projected and retracted positions and having an opening extending transversely therethrough providing an edge portion on the inner side of said retractor, a dogging unit movable through said opening transversely of said retractor between undogging and dogging positions, said dogging unit including a dogging bar having a rearwardly extending dogging finger normally disposed in said opening and a latching bar lying in the same plane as said dogging bar adjacent said edge portion and having its inner end extending into said opening, means pivotally connecting said bars intermediate their ends, a projection on said dogging finger overlying the inner end of said latching bar to provide a stop therefor, a spring attached to and pressing the outer ends of the bars together to thereby urge the inner end of the latching bar toward said edge portion, a hollow pushbutton attached to the outer ends of said bars and containing said spring, said pushbutton, when depressed, shifting the dogging unit into dogging position, a latching abutment on the inner end of said latching bar engageable with said edge portion to retain the dogging unit in dogging position, and separate spring means for shifting said dogging unit to undogging position upon retraction of said retractor and disengagement of said edge portion from said latching abutment,

said stop preventing said latching bar from following the retractor as it moves toward retracted position.

8. In a door lock, a retractor for a latch bolt movable transversely of the lock between projected and retracted positions and having an opening extending transversely therethrough providing an edge portion on the inner side of said retractor, inner and outer independently rotatable spindles each having rollback means thereon for actuating said retractor, said outer spindle having a slot therein normally aligned with the opening in said retractor and with a slot in a stationary portion of said lock, an abutment in said inner spindle, a dogging bar contained within said inner spindle and having a rearwardly extending dogging finger on its inner end portion normally disposed in said opening and a cam surface aligned with said abutment, a latching bar pivotally connected to said dogging bar and having a free inner end extending into the opening in said retractor adjacent said edge portion, spring means acting upon said bars and urging the inner end of said latching bar toward said edge portion, a pushbutton connected to the outer end of said dogging bar and adapted upon depression to move said dogging bar and said latching bar inwardly in said inner spindle to cause engagement of said cam surface with said abutment whereupon said dogging bar is cammed rearwardly relatively to said lock and toward said latching bar against the force of said spring and into dogging position wherein said dogging finger is disposed in said slots thereby preventing rotation of said outer spindle, said latching bar having a latching abutment on its inner end portion and being movable by said spring to cause latching engagement of said latching abutment with the edge portion of said retractor to thereby retain the dogging bar in dogging position, and separate spring means for returning said dogging bar and said latching bar to undogging position upon movement of said retractor to retracted position and disengagement of said edge portion from said latching abutment.

9. In a door lock, a retractor for a latch bolt movable transversely of the lock between projected and retracted position and having an opening extending transversely therethrough providing an edge portion on the inner side of said retractor, inner and outer independently rotatable spindles each having rollback means thereon for actuating said retractor, said outer spindle having a slot therein normally aligned with the opening in said retractor and with a slot in a stationary portion of said lock, an abutment in said inner spindle, a dogging bar contained within said inner spindle and having a rearwardly extending dogging finger on its inner end portion normally disposed in said opening and a cam surface aligned with said abutment, said dogging finger having a stop portion thereon extending toward the outer end of the dogging bar, a latching bar disposed rearwardly of said dogging bar in edge-to-edge relationship therewith, a projection extending from said latching bar intermediate its ends into a recess in the adjacent edge of said dogging bar whereby said bars are arranged for relative pivotal movement, the inner end portion of said latching bar extending into the opening in said retractor adjacent to said edge portion and under said stop portion, a spring member acting upon the outer ends of said bars and biasing the inner end of the latching bar toward said edge portion and into engagement with said stop portion, said spring member also retaining said projection in said recess, a hollow pushbutton secured to the outer ends of said bars and containing said spring, said pushbutton being depressible to move said bars inwardly in said inner spindle to cause engagement of said cam surface with said abutment whereupon said dogging bar is cammed rearwardly relatively to said lock and toward said latching bar against the force of said spring and into dogging position wherein said dogging finger is disposed in said slots thereby preventing rotation of said outer spindle, said latching bar having a latching abutment on its inner

end portion and being movable by said spring to cause latching engagement of said latching abutment with the edge portion of said retractor to thereby retain the dogging bar in dogging position, and separate spring means for returning said dogging bar and said latching bar to undogging position upon movement of said retractor to retracted position and disengagement of said edge portion from said latching abutment; said stop member preventing movement of said latching bar with said retractor.

10. In a door lock, a retractor for a latch bolt having an opening extending transversely therethrough providing an edge portion on the inner side of said retractor, a dogging unit movable through said opening transversely of said retractor between an outward undogging and an inward dogging position, said dogging unit including a dogging bar and a latching bar, said latching bar being movably mounted on said dogging bar and having an inner free end portion extending into the opening in said retractor adjacent said edge portion thereof, said latching bar having its inner free end resiliently biased away from said dogging bar and toward said edge portion, a latching abutment on the inner end portion of said latching bar adapted to engage said edge portion and disposed outwardly thereof when the dogging unit is in undogging position, a pushbutton attached to the outer end of said dogging unit and adapted, upon depression thereof, to shift said dogging unit inwardly into dogging position, the bias of the free end of said latching bar then urging said latching abutment into engagement with said edge portion whereby said dogging unit is held in dogging position, stop means on one of said bars limiting movement of the inner end of the latching bar and preventing the inner end portion of said latching bar from following said edge portion of the retractor when said retractor moves toward retracted position, and spring means for shifting said dogging unit into undogging position upon retraction of said retractor and disengagement of said edge portion from said latching abutment.

11. In a door lock, a retractor for a latch bolt having an opening extending transversely therethrough providing an edge portion on the inner side of said retractor, a dogging unit movable through said opening transversely of said retractor between an outward undogging and an inward dogging position, said dogging unit including a dogging bar and a latching bar, said latching bar being pivotally mounted on said dogging bar and having an inner free end portion extending into the opening in said retractor adjacent said edge portion thereof, spring means acting upon said bars and biasing said inner end portion of the latching bar away from said dogging bar and toward said edge portion, a latching abutment on the inner end portion of said latching bar adapted to engage said edge portion and disposed outwardly thereof when the dogging unit is in undogging position, a pushbutton attached to the outer end of said dogging unit and adapted, upon depression thereof, to shift said dogging unit inwardly into dogging position, said spring means then urging said latching bar about its pivot to move said latching abutment into engagement with said edge portion whereby said dogging unit is held in dogging position, stop means on said dogging bar limiting movement of said latching bar and preventing its free end from following said edge portion when said retractor moves toward retracted position, and separate spring means for shifting said dogging unit to undogging position upon retraction of said retractor and disengagement of said edge portion from said latching abutment.
